VANDERHYE P.C.

(57) **CLAIM**

The ornamental design for a clip, as shown and described.

DESCRIPTION

FIG. 1 is a front perspective view of a clip showing my new design;

FIG. 2 is a rear perspective view thereof;

FIG. 3 is an exploded perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines and unshaded areas adjacent to the broken lines depict portions of the clip that form no part of the claimed design.

1 Claim, 9 Drawing Sheets
